HASSOCK

Evalin S. Gilbert, 2121 N. Bay Shore Drive,
Miami, Fla. 33137

Filed Nov. 20, 1972, Ser. No. 308,040

Term of patent 14 years

Int. Cl. D6—02

U.S. Cl. D6—36

FIG. 1

FIG. 2

FIG. 1 is a side elevational view of a hassock incorporating my new design; and

FIG. 2 is an end elevational view of the hassock of FIG. 1.

The hassock has a conventionally tufted top while the side and end of the article not shown are mirror images of the side and end shown, respectively.

I claim:

The ornamental design for a hassock, substantially as shown and described.
